UNITED STATES PATENT OFFICE.

IDA BROWN, OF SAN FRANCISCO, CALIFORNIA.

BUTTONHOLE-GUIDE.

1,141,761.

Specification of Letters Patent. Patented June 1, 1915.

Application filed June 23, 1914. Serial No. 846,824.

To all whom it may concern:

Be it known that I, IDA BROWN, a citizen of the United States, residing at San Francisco, in the county of San Francisco and 5 State of California, have invented certain new and useful Improvements in Button-hole-Guides, of which the following is a specification.

This invention relates to button hole 10 guides, and one of the principal objects of the invention is to provide a simple device to assist in the working of button holes accurately and quickly.

Another object of the invention is to provide a button hole guide having a straight edge and a pin connected in parallel relation to said edge, said pin forming a guide for the thread in forming the button hole, and said pin adapted to be changed in position 15 from one edge of the button hole to the other readily so that the button hole can be worked accurately by an unskilled person, and more quickly than can be done by the usual method employed for making button 20 holes.

These and other objects may be attained by means of the construction illustrated in the accompanying drawing, in which,

Figure 1 is a perspective view of a button 30 hole guide made in accordance with this invention, Fig. 2 is a sectional view taken on the line 2—2 of Fig. 1, looking in the direction indicated by the arrows, and Fig. 3 is a sectional view taken on the line 3—3 of Fig. 35 1, looking in the direction indicated by the arrows.

Referring to the drawing, the numeral 1 designates the base plate of the button hole 40 guide preferably formed of nickel plated brass or other smooth material, said plate having at its opposite ends slots 5 and 6. The plate 1 is practically flat upon opposite sides and one edge of the plate 1 is provided with a plane straight guide edge 7, and extending from one end of said edge 7 is a hook 8. Mounted in the said hook 8 is the shank portion 9 of a guide needle 10, said shank portion being provided with a head 11 and offset portion 12, and the main portion 45 of said pin being straight from the offset 12 to the opposite pointed end 13, and said pin being disposed in parallel relation to the straight edge 7 of the guide plate.

Formed on the plate and extending parallel to the edge 7 is a guide member 14 for the 55 point of the pin or needle 10.

The manner of using the device may be briefly described as follows: A button hole slit is formed in the material of the required length and the button hole guide is secured 60 to the material with the needle 10 extending across in line with the slit and to hold the guide in place, pins are secured in the slots 5 and 6, said pins extending through the material to hold the plate in place. One edge of 65 the button hole is worked by whipping the thread over the needle 10 and into the material, said needle serving as a guide for the working needle carrying the thread. After one side of the bottom hole is worked, the 70 pins are removed from the material at the slots 5 and 6 and the plate is turned upon the needle 10 as a pivotal point to the opposite side of the button hole.

From the foregoing it will be obvious that 75 a button hole guide made in accordance with this invention will insure a good straight even uniform button hole stitch, for the reason that the needle carrying the thread can be carried around the needle or pin 10 as a 80 guide and thus insure uniform stitches and even work.

Slight changes may be made in the details of construction without departing from the spirit and scope of the invention as defined 85 in the claims.

What is claimed is:

1. A button hole guide comprising a plate having a slot at each end thereof, and a pin provided with an offset portion mounted in 90 one end of the plate and provided with a guide at the opposite end, said pin forming a guide for the loop in the thread for forming the button hole, and said plate having a plane edge lying parallel to the pin. 95

2. A button hole guide comprising a plate having oppositely disposed slots for securing the plate to the material by means of pins extending through said slots, said plate having a straight edge, and a pin mounted 100 in the plate and disposed parallel to the straight edge, said pin forming a guide and being connected at one end to a keeper.

3. A button hole guide comprising a plate having a slot at each end thereof and an off- 105 set pin pivoted to one side or end of the

plate and extending across parallel with one edge of said plate, said pin having a keeper on the plate.

4. A button hole guide comprising a flat plate having a slot at each end thereof, a pin pivoted near its head to one side or end of said plate, said pin having a head at one end and a point at the opposite end, said pin having an offset near the head and said pin

adapted to lie parallel to one of the straight edges of the plate.

In testimony whereof I affix my signature in presence of two witnesses.

MRS. IDA BROWN.
